E. J. LEES.
REVERSIBLE TOOL CONTRIVANCE.
APPLICATION FILED APR. 24, 1916.

Patented Oct. 24, 1916.

Inventor:
Ernest J. Lees
by his atty

Law B. offutt.

UNITED STATES PATENT OFFICE.

ERNEST J. LEES, OF CLEVELAND, OHIO, ASSIGNOR TO THE LEES-BRADNER COMPANY, OF CLEVELAND, OHIO.

REVERSIBLE-TOOL CONTRIVANCE.

1,202,195.

Specification of Letters Patent.

Patented Oct. 24, 1916.

Application filed April 24, 1916. Serial No. 93,142.

To all whom it may concern:

Be it known that I, ERNEST J. LEES, a citizen of the United States, residing at Cleveland, in the county of Cuyahoga and State of Ohio, have invented a new and useful Improvement in Reversible-Tool Contrivances, of which the following is a specification, the principle of the invention being herein explained and the best mode 10 in which I have contemplated applying that principle, so as to distinguish it from other inventions.

The subject matter of this application pertains to a doubly reversible tool contrivance and necessarily to a construction of the tool according to which the advantages of 15 my alleged invention are achieved.

I have selected a tool known as a cutter of the ring type for the purpose of exemplifying the practicability of my improvement. In ring cutters no lead is given the cutting edges.

Cutters which could be detached from a driving member have been in use a long 25 time. By changing the mounting it became possible to effect either a right-hand or a left-hand cut. Such cutters have heretofore, however, been secured by a nut applied to the end of the driving member and 30 abutting one side or the other of the cutter. This limited the approach of the tool in "dead end" work whether in a closed bore or exteriorly adjacent a shoulder or other projection. On the other hand such cutters 35 as were made integral with one end of a tapered shank entailed an extravagance in regard to the needless expense of the metal composing such shank. Moreover, while they could cut close up to a "dead end," 40 they were limited to either a right-hand or to a left-hand cut whether used interiorly or exteriorly. In other words they were not reversible for both interior and exterior work, hence permitted of only a double use.

45 My contrivance makes possible the accomplishment of a quadruple use or double reversibility and at the same time avoids a waste in material and permits of close "dead end" operation. In short, I have 50 succeeded in combining the advantages of both kinds of cutters till now known and used and avoiding the disadvantages of each. The crux of the idea, in so far as concerns structural alteration, is exceedingly

simple. It consists in sufficiently enlarging 55 opposite ends of the bores of detachable cutting tools in order to accommodate a securing nut in one or the other of the recesses so formed, and further, in limiting the insertion of the driving member 60 (spindle or arbor) into the bore of the tool so that no part of such nut and no part of the driving member projects beyond the tool. I do not hesitate to mention that many detachable cutting tools 65 have been provided with enlarged bore extremities, but in every instance for some special reason other than the one now given. One common reason for thus incidentally enlarging the end of detachable cutter bores 70 was to make its key-way conform in width to some given standard of measurement.

At present when long cutters, say five inches or more, are manufactured, error is likely to present itself owing to warpage 75 and shrinkage. This in itself has also been known to those who were practised in the art, and as a result sectional or composite cutters have been developed. I have successfully adapted my reversibility invention 80 to such a composite structure and believe that the steps required to accurately accomplish it constitute a novel method of manufacture.

Obviously, the use of a spanner nut for 85 occupying the enlarged portion of the bore is more feasible and as to this minor particular a change exists also. I would have it expressly understood that I in no wise limit myself to this specific application or 90 embodiment of my invention, which I have selected as a basis for illustrating and describing my invention merely for the purpose of rendering a clear and comprehensive understanding of the novel features 95 thereof and of the scope of the appended claims.

Adverting to the drawing: Figure I is a longitudinal section of a contrivance embodying my invention together with a 100 broken view of a work piece to be threaded thereby. Fig. II is an elevation of the tool itself as mounted. Fig. III is an end view of Fig. II. Fig. IV is a sectional view showing separated portions of a modified 105 composite tool. Fig. V depicts the modification, partly in section, as assembled.

An observation of Fig. I makes clear how

a suitable driving arbor 1, having a key 2 and usual threaded end 3, is limited as to its intersection with a tool 4 which has an interjacent portion fashioned with a complementary key-way 5. In other words, the reduced threaded extremity 3 of the arbor is not permitted to project beyond the free end of the tool, in order that the latter may operate close up to a shoulder 6 of a given work piece upon which, as shown in

10 Fig. I, threads 6 have already been imparted. Anyone familiar with the art will perceive that the same advantage may be had in cutting internal threads beginning 15 close up to the end of a closed bore.

The tool 4 proper of high speed steel is fashioned with a series of cutting teeth 8 in staggered arrangement about its periphery and with a full tooth at each end as appears 20 in Figs. I and II. In order to effect a true staggered relationship there should be an even number of flutes 9 as shown in Fig. III. The teeth 8 are located in parallel rings. They are radially relieved as the shade lines

25 thereon in Fig. III disclose. The bore of the tool has each of its end portions 10 somewhat enlarged, and the key-way 5 restricted to its interjacent portion. In this manner an internal space is afforded for the accommodation of a spanner nut 11 so that its outer side is either flush or depressed with respect to the end of the tool. It should be understood that the tool is symmetrical in the sense of having its ends alike, such that

35 it may be feasibly reversed and the spanner nut 11 caused to occupy a portion of either one of the bore ends 10 according to whether a right-hand or left-hand thread is desired. Thus either direction of thread 40 may be cut either externally or internally and all four close up to what is known as a dead end.

The modification illustrated in Figs. IV and V involves a sectional cutter which may 45 be made true regardless of its length and in this way. An arbitrary plurality of blanks say, three, 12, 13 and 14 are first fashioned with internal key-ways, then keyed (in final size) to an arbor which is slightly 50 smaller than the one upon which they are intended eventually to be operated. This is necessary because the blanks are later ground internally. Thereafter the blanks are fluted, relieved and sharpened while 55 held on such manufacturing arbor. Some definite starting point is assumed in the case of each blank so that when assembled they cut in correct continuation of each other. The blanks are held on the arbor to bring 60 all the cutter sections to the same diameter, to keep the outline parallel and to retain the correct diameter during the sharpening. In other words all the sections must be kept in line which would be difficult if not impossible if made separately. After the sections

have been hardened their ends are ground until the pitch is corrected. The two sections 12 and 14 are here provided each with a single bore enlargement designated by the reference numerals 15 and 16 respectively. These enlarged bore ends are then of course 70 at the two ends in fact when all three are assembled as in Fig. V. Thus the quadruple use of my invention is similarly made possible.

75 I claim:

1. A reversible thread milling cutter provided with a bore extending therethrough, said bore being enlarged at each end for the purpose specified.

80 2. A reversible thread milling cutter of the ring type having plain ends and a bore extending therethrough, said bore being of larger size at its ends than at its middle, said tool being provided with peripheral cutting edges at each end and at definite distances therebetween, the middle of said bore furthermore fashioned with angularly related surfaces.

85 3. A reversible thread milling cutter contrivance comprising the combination of a rotatable driving member, a hollow symmetrical tool mounted upon one end thereof so as to rotate therewith, said tool having circularly disposed teeth definitely positioned between its own ends, and a member for fastening said member and tool together, said member being positioned within the confines of said tool.

90 4. A reversible thread milling cutter contrivance comprising the combination of a driving member, a hollow tool having peripheral teeth mounted upon one end thereof so as to move therewith, and means located between the ends of said tool for fixing 100 it to said member.

95 5. A reversible thread milling cutter contrivance comprising the combination of a rotatable member, a hollow symmetrical tool keyed thereto and having peripheral teeth, and means located between the ends of said tool for fixing it to said member.

100 6. A reversible thread milling cutter contrivance comprising a driving member, a hollow tool mounted thereon so as to rotate therewith, said tool having two symmetrical flat ends and teeth arranged therebetween, the end of said member being inclosed by said tool, and means for holding said tool in place and located interiorly thereof.

105 7. A reversible thread milling cutter contrivance comprising a driving member having a threaded end, a hollow tool keyed thereto, said tool having teeth between its ends and substantially flat ends, an end of said member being wholly inclosed by and spaced from said tool, and a nut secured to said end and wholly disposed within the confines of such space for the purpose specified.

110 8. A reversible thread milling cutter con-

trivance comprising a rotatable driving member, a cylindrical cutting tool of the ring type having teeth around its periphery and keyed thereto so as to wholly inclose one 5 end thereof, the bore of said tool being furthermore enlarged at each end to provide a space about the inclosed end of said

member, and means accommodated in said space for securing said member and tool to each other whereby to enable either flat end 10 of the tool itself to abut a dead end of a given work piece.

Signed by me, this 18th day of April, 1916.
ERNEST J. LEES.
